UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

TRACK LINER.

Application filed December 26, 1923. Serial No. 682,769.

To all whom it may concern:

Be it known that I, BENJAMIN WOLHAUPTER, citizen of the United States, residing at 28 Neptune Ave., New Rochelle, in the county of Westchester and State of New York, have invented certain new and useful Improvements in Track Liners, of which the following is a specification.

This invention relates to track liners, 10 adapted for use in relining railroad tracks, and has for its primary object the provision of a simple and economical device which meets all of the practical requirements of a track liner and is capable of being easily carried about or transported and readily positioned under the rail.

When shifting a rail laterally through the medium of a crowbar or other lever, it is necessary in order to obtain the greatest efficiency, to provide a fixed fulcrum point for the lever. It is also desirable to have a series of fixed fulcrum points for the lever whereby the lever may be progressively shifted from one point to another and thereby gradually and easily shift the rail without lifting. Thus, two essential features are necessary, first a rail engaging lever, and, second a series of fixed fulcrum points for the lever.

To that end, the invention contemplates a fulcrum plate or ballast rest of adequate area which is adapted for use with a crowbar or other lever and which will provide the essentials above pointed out and reduce to a minimum the labor required for relining the track.

Another object of the invention is to provide a plate which can be cheaply manufactured and which can be readily used with safety from the outside of the track.

A further object of the invention is to provide a fulcrum plate which is susceptible embodiment in a form which affords a wide range of selection in the fulcrum point.

With these and other objects in view, which will more readily appear as the nature of the invention is better understood, the same consists in the novel construction, combination and arrangement of parts hereinafter more fully described, illustrated and claimed.

Preferred and practical embodiments of

my invention are shown in the accompanying drawings, in which:—

Figure 1 is a view showing more or less diagrammatically the application of my invention.

Figure 2 is a view similar to Figure 1 but showing in dotted lines the adjusted position of the track.

Figure 3 is a plan view of the track liner plate.

Like reference characters designate corresponding parts throughout the several figures of the drawings.

In carrying out the invention the plate or base A may be manufactured in various ways, and of different materials such as for instance as malleable iron or pressed steel, 70 and because of its comparatively shallow depth it is adapted to be readily positioned on the ballast under a rail.

One of the features of the plate A is that it is formed on its upper side with a series 75 of transversely disposed fulcrumming shoulders 1 and on its underside with a series of transversely disposed anchoring shoulders or abutments 2 which present very wide and broad surfaces for engaging the ballast. 80

Preferably, but not necessarily, the said fulcrumming and anchoring shoulders extend entirely across the plate and are arranged in a longitudinal series and result from corrugations formed in the body of the plate. 85 The shoulders are disposed in spaced relation and each corrugation includes a substantially vertical wall 3 forming on one face the fulcrum shoulder 1 and on the other face the anchoring shoulder 2, and an inclined wall 4. The plate is reversible and consequently when the plate is reversed from the position shown in Figure 2, the anchoring shoulders 2 constitute the fulcrum shoulders, and vice versa. The plate when re- 90

versed is not only turned upside down, but, of course, is turned end to end. One end of the plate is formed with a hand opening 5 for use in transporting or positioning the plate.

In operation, the plate is readily positioned under the rail from the outside of the track and if the ballast is high that is, close to the rail, it is only necessary to remove a portion of the ballast in order to insert the plate because of the fact that the plate is of

comparatively little depth. By reason of the inclined walls 4 of the corrugations, the plate can be readily slid over the ballast and into proper position, and when pressure is applied to the plate the anchoring shoulders will become instantly seated in the ballast. Thus, the plate will be securely retained against longitudinal movement and consequently the fulcrum shoulders will remain fixed. After the plate has thus been positioned under the rail a crowbar 6 or other suitable lever or lining bar is fulcrumed against the fulcrum shoulder 1 which is substantially under the outer edge of the rail. The lever 6 upon upward movement thereof will engage the base flange 7 of the rail and inasmuch as the anchoring shoulders 2 firmly engage the ballast, the fulcrum point will be fixed and consequently the track will be shifted laterally. The track is shifted laterally by degrees, and to this end the lever will be repositioned to engage the fulcrum shoulders of the plate in progression until the track has been shifted the required distance.

From the foregoing it will be apparent that the present invention also lends or adapts itself to crow-bars which vary as to the length of their fulcrum ends which engage the fulcrum plate and the rail flange, and that condition is accommodated by making the corrugations in the fulcrum plate closer or farther apart as such conditions may require.

Without further description it is thought that the features and advantages of the invention will be readily apparent to those skilled in the art, and it will of course be understood that changes in the form, proportion and minor details of construction may be resorted to, without departing from

the spirit of the invention and scope of the appended claims.

I claim:

1. A corrugated fulcrum plate, the corrugations forming on its underside a series of spaced anchoring shoulders. 45

2. A corrugated fulcrum plate for track liners, the corrugations forming on its upper side a series of spaced fulcrum shoulders and on its underside a series of spaced anchoring shoulders. 50

3. A transversely corrugated fulcrum plate, the corrugations extending entirely across the plate, and forming on its underside a series of spaced anchoring shoulders. 55

4. A transversely corrugated fulcrum plate for track liners the corrugations extending entirely across the plate, and forming on its underside a series of spaced anchoring shoulders and on its upper side a series of spaced fulcrum shoulders. 60

5. A reversible corrugated track liner plate.

6. A reversible corrugated track liner plate having on its upper and lower sides respectively a series of spaced fulcrum shoulders and a series of spaced anchoring shoulders, said shoulders being disposed transversely of the plate and extending across the entire width thereof. 65

7. A reversible corrugated track liner plate, one wall of each corrugation being disposed in a substantially vertical plane, one face of each wall forming a fulcrum shoulder and the other face thereof forming an anchoring shoulder. 75

In testimony whereof I hereunto affix my signature in the presence of two witnesses.

BENJAMIN WOLHAUPTER.
